SEPARATING AND CLASSIFYING APPARATUS

Walter Philip Laesch, Brighton, Colo., assignor to
Horace Wills, Denver, Colo.

Application May 11, 1933, Serial No. 670,416

3 Claims. (Cl. 209—479)

This invention relates to apparatus operable to separate comminuted materials into groups marked by a difference in specific gravities, and more particularly to apparatus operable to separate gold and other heavy metals from placer sands and ore pulps, and has as an object to provide an improved apparatus of the character described which is continuously and efficiently operable to separate and entrap the heavier particles from placer sands and ore pulps.

A further object of the invention is to provide an improved separating and classifying apparatus having a separating table arranged for continuous agitation with a motion having an improved separatory effect on the material passed thereover.

A further object of the invention is to provide an improved separating and classifying apparatus having two simultaneously operable, separatory stages arranged to act successively on the material being treated.

A further object of the invention is to provide an improved separatory table in a separating and classifying apparatus.

A further object of the invention is to provide improved means for actuating the separatory table of a separating and classifying apparatus.

A further object of the invention is to provide an improved construction and arrangement of elements in a separating and classifying apparatus whereby is produced a self-contained, lightweight, easily transportable unit having low initial and operating costs, long life and efficient operation.

My invention consists in the construction, arrangement and combination of elements hereinafter set forth, pointed out in my claims and illustrated by the accompanying drawings, in which—

Figure 1 is a side elevation of one structural embodiment of the improved apparatus as assembled and ready for practical use. Figure 2 is a plan view of the showing of Figure 1. Figure 3 is a fragmentary detail section, on an enlarged scale, taken on the indicated line 3—3 of Figure 2, dotted lines indicating alternative positions of some of the elements of the apparatus. Figure 4 is a fragmentary detail section, on the same scale as Figure 3, taken on the indicated line 4—4 of Figure 2. Figure 5 is an end elevation, partly in section and on the same scale as Figures 3 and 4, taken on the indicated line 5—5 of Figure 1, certain elements of the assembly not essential to an understanding of the operation of the apparatus shown being omitted

for the sake of clarity. Figure 6 is a plan view of an adjustable eccentric employed in the assembly. Figure 7 is a side elevation of the showing of Figure 6.

In the construction of the improvement as shown, complementary, skeletonized, rectangular frames 10 and 11, formed of any suitable material in any desired manner and having lengths greater than their heights, are disposed in spaced, parallel relation and interconnected in any suitable manner, as for instance by means of transverse straps 12, to form a rigid frame constituting the base of the apparatus. Within the base formed as above described and fixed thereto, is mounted a power generating or transmitting device, such as a jack-shaft, electric motor or internal-combustion engine, the latter being indicated at 13 in the drawings, and a water pump, of any suitable type, indicated by the numeral 14, is fixed within the base adjacent and in driven relation with the power unit

13. Mounted for rotation about its axis, a shaft 15 is vertically-disposed adjacent one end of the base frame and suitably supported by means of bearings carried by the transverse straps 12, said bearings preferably being so positioned as to mount the shaft 15 on the longitudinal median line of the base frame, a suitable pulley 16 being fixed to the intermediate portion of the shaft 15 and operatively connected with the power unit

13. The shaft 15 is arrested somewhat below the upper bar of the base frame and is provided at its upper end with a flange or plate 17 centered on said shaft and rotatable therewith, to which plate 17 is adjustably secured a similar plate 18 whereon is centered a perpendicularly related socket member 19, the arrangement of plates 17 and 18 being such as to permit adjustment of the spacing between centers of the shaft 15 and socket member 19 while maintaining said latter elements in axial parallelism. Any suitable specific construction and arrangement of the plates 17 and 18 and their interconnecting elements may of course be employed to accomplish the desired end, that construction and arrangement shown in Figures 6 and 7 being simple and efficient and comprising straight, parallel side margins on opposite sides of the plate 17 and straight, parallel flanges on opposite sides of the plate 18 arranged to engage against and slide along the straight portions of the plate 17, bolts 20 engaging through the plate 17 on opposite sides of the shaft 15 and through elongated slots in the plate 18 serving to firmly clamp said plates together, the torque transmitted from the

plate 17 to the plate 18 acting through the flanges of said latter plate rather than through the bolts 20. It is of course obvious that the bolts 20 may be loosened to permit adjustment of the plate 18 on and relative to the plate 17 for variation in the spacing between centers of the shaft 15 and socket member 19 and subsequently tightened to maintain the spacing as set.

Supported by and above the base frame, a supplemental floating frame formed of spaced, parallel side members 21 and 22 interconnected by transverse members 23 and 24 is mounted and arranged for limited motion in a horizontal plane, anti-friction devices 25 fixed adjacent the corners of the base frame and engaging plate-like portions of the floating frame being shown as one convenient and satisfactory means of supporting the latter from and relative to the former, though it is obvious that the specific supporting means may be varied structurally as may be desired. A stud 26 depends from the transverse member 23 midway the members 21 and 22 and has its lower end received in the socket member 19, thus linking one end of the floating frame to the shaft 15, and a relatively long stem 27 extends horizontally from the transverse member 24 on the longitudinal median line of the floating frame, said stem 27 being slidingly received through a horizontal bearing 28 which is in turn pivotally mounted for actuation through horizontal arcs in a bearing 29 carried by the base frame, thus linking the adjacent end of the floating frame to and for limited motion relative to the base frame. With the arrangement of elements shown and described, it is apparent that when the socket member 19 is set eccentrically of the shaft 15 and the latter rotated, a rotary motion corresponding in radius to the amount of eccentricity in the socket member setting will be imparted to the end of the floating frame adjacent the stud 26 and the end of the floating frame adjacent the stem 27, will, by virtue of the linkage engaging said stem, have motion through an oval orbit having a longitudinal axis equal to the diameter of the rotary motion at the other end of the frame, points of the floating frame intermediate its ends having orbits more or less oval in form and varying according to the exact position of said points relative to the extreme orbits described.

The transverse members 23 and 24 extend at each end beyond the adjacent side members 21 and 22, the extending portions of said transverse members being bent upwardly to vertical position 55 along the side members and extending above the latter, as shown at 30, the upwardly extending portions of said transverse members being provided with vertically opening slots 31 extending to the upper margins of the side members 21 and 22. A table member formed with a bottom 32, sides 33 and 34, and a closed end 35 is arranged to be removably, adjustable and replaceably carried by the floating frame previously described, said table member having a width slightly less than the transverse spacing between corresponding vertical lugs 30 and a length somewhat greater than the longitudinal spacing between said lugs, said table member being provided with transverse supporting rods 36 extending laterally on each side of the table member and so spaced and arranged as to be received in the slots 31 of the vertical lugs 30 and be clamped thereagainst by means of nuts 37 to rigidly clamp said table member in the desired relation with the floating frame. Various 70 alternative means may be employed to secure and

position said table member relative to the floating frame, which means, however, should provide for relative elevation of either end of the table member, when desired, which adjustment is of course a function of the mounting shown and described. The table member is positioned with its open end adjacent the shaft 15 and related connections, so that said open end of the table member is subjected to the maximum rotative motion imparted by said shaft. The bottom 32 of the table member is not plane throughout its entire extent but is provided throughout its major portion with semispherical cups or recesses 38, formed in or attached to said bottom 32 in any suitable manner, said cups or recesses 38 each merging in a smooth curve with the adjacent portions of the bottom member and presenting no sharp edges or rough angles. The cups or recesses 38 are preferably arranged in close proximity in some suitable pattern, it being preferable that adjacent cups be staggered longitudinally of the apparatus. Between the open end of the table member and the most nearly adjacent row of cups or recesses 38 is disposed a transverse bar or riffle 39, said bar or riffle 39 being channeled on the side adjacent the cups or recesses 38 and arranged with oblique end portions extending angularly from a laterally disposed central portion and diverging toward the closed end of the table member until engagement with the side walls of the latter is had, thus completely obstructing the discharge end of the table member to an extent measured by the depth of the bar or riffle 39. The side members 21 and 22 of the floating frame are extended longitudinally beyond the base frame and terminate in corresponding upturned ends 21' and 22', respectively, between the terminals whereof a bar 40 is horizontally disposed and journaled for rotation. Beneath the overhang of the table member at its open end, a rod 41 is mounted transversely between the members 21 and 22, on which rod 41 is hingedly secured one margin of a housing 42 surrounding and supporting a shallow, circular pan 43, the latter preferably being formed as a depressed portion in the bottom of the housing 42 and being dished slightly so that its central portion is lower than its margin. The housing 42 has a width less than the spacing between the members 21 and 22 so that it may move freely therebetween, and a bar 44 pivotally mounted transversely of the housing 42 beneath the bar 40, supports a threaded stem 45 which rises loosely through a boss centrally of the bar 40 to threaded engagement with a wheel nut 46, or similar device, bearing against said bar 40 whereby the vertical adjustment of the housing 42 and pan 43 may be manually controlled, dotted lines in Figure 3 indicating the possible range of movement of said housing and pan about the pintle 41. It is of course obvious that the mechanical arrangement for adjusting and controlling the relative elevation of the housing 42 and pan 43 may be varied, and may be made fully automatic by ratchet connection with the shaft 15, if desired, the construction illustrated and described being but typical and presented in a simple and efficient form. The overhanging relation of the discharge end of the table member in respect of the housing 42 and pan 43 permits material discharged from said table to be received in said housing and pan for such further treatment as will be herein-after described, while the mounting of the pan and housing on the floating frame subjects said elements and their contents to the motion im- 75

ported to said floating frame by the shaft 15 and its related elements.

Removably and replaceably mounted on stand arms 47 rising from the base frame on either side 5 of the closed end of the table member, a hopper 48 is positioned transversely of and above said closed end of the table, said hopper preferably being formed with a sloping bottom converging inwardly and downwardly to a central aperture 10 arranged to discharge onto the table member adjacent its closed end and a baffle plate 49 horizontally disposed within said hopper in overlapping relation with and above said aperture, it being the function of said baffle plate to retard 15 discharge from said hopper and provide relatively uniform feed from the latter. A hose or equivalent connection 50 is led from the outlet of the pump 14 to the hopper 48 where it operatively connects with an elongated nozzle 51 disposed 20 within said hopper in position to wash material through the latter and onto the table beneath.

The apparatus assembled and arranged as shown and described may be employed as either a "wet" or "dry" machine in the treatment of 25 placer sands and ore pulps for the extraction of values, according to the nature of the material being treated and the availability of water. When used as a "dry" machine, the pump 14 is not 30 operated and dry material is fed in any convenient manner to the hopper 48 whence it is gravity fed to the table member beneath while the floating frame, and consequently the table member, is actuated through the shaft 15 by the power unit 13. The motion imparted to the table 35 member may not be varied in character, but may be varied in amplitude by changing the eccentricity of the socket member 19 relative to the shaft 15, and may be varied in its effect on the material under treatment by variation in the 40 speed of the shaft 15. As material is fed to the active table member, it spreads smoothly and evenly over said table due to the character of the motion imparted to the latter, the heavier particles of the material being naturally shaken 45 into the bottoms of the cups or recesses 38 where they are entrapped, whorls or circular eddies formed about each of said cups or recesses by virtue of the rotary motion of the table member aiding in concentrating the heavier particles in 50 said depressions. When the table member has been filled with material to the depth of the bar or riffle 39, the lighter materials will escape over said element and discharge within the housing 42 and find their way into the pan 43, which 55 latter, being normally horizontally disposed and agitated, acts in the nature of a manually operated gold pan and exerts a further separatory effect on the material to the end of capturing such values as may have escaped from the table 60 member. The channeled character of the bar or riffle 39 minimizes possibility of escape of values from the table member, since heavier particles coming against said member 39 may not rest there and build up to the point of escape, 65 but, on the contrary, such particles enter the channel and are moved transversely of the table during the agitation of the latter until the particles are again thrown back under the influence of the recesses 38 through one or the other of the 70 oblique portions of the element 39. Any suitable amalgamating agency, such as mercury, may be deposited in the recesses 38 to aid in the entrapment of the values, such expedients being common and well-known, and instead of being operated in a horizontal plane, one end or the other 75

of the table member may be relatively elevated to enhance or retard the speed with which the material moves across said table. When used as a "wet" machine, the operation is in all respects the same as above set forth, save that the pump 14 is operated to provide a continuous flow of water to and through the hopper 48. After the apparatus has been operated the desired length of time, or when the recesses 38 are substantially filled with values, the operation is arrested 10 and the material accumulated in the recesses, usually consisting of values mixed with heavy black sands, removed from the table and placed in the pan 43, a convenient method of effecting this clean-up being to elevate the open end of 15 the table member and wash the accumulation thereon through a cleanout port 52 adjacent the closed end of said table and into a suitable container, a jet operatively connected with the pump 14 through the outlet branch 53 of the latter 20 facilitating this operation. It is of course apparent that an outlet passage for clean-up purposes may be provided leading through or under the riffle 39, in which even the closed end of the table member would be elevated. After the accumulation from the recesses 38 has been deposited in the pan 43, the apparatus is again operated and the pan 43 with its housing 42 slowly lowered through the agencies previously described, this 25 operation being continued until all gangue has been separated from the values, which latter remain in the angle formed between the pan 43 and its housing 42. In operative effect, each of the recesses 38, as well as the pan 43, has the characteristics of the conventional prospector's gold 30 pan, and the speed and amplitude of the table motion can be so adjusted as to give a remarkably efficient separation and recovery on various 35 types and characters of placer sands and ore pulps.

Since it is obvious that many changes and modifications in the specific form, construction and arrangement of the elements shown and described may be had without departing from the spirit of my invention, I wish to be understood as being limited solely by the scope of the appended claims, rather than by any details of the illustrative showing and foregoing description.

I claim as my invention—

1. Apparatus of the character described comprising, in operative combination, a fixed base, a frame carried by said base and movable horizontally thereof, pivotal means fixed to said base and slidably engaging one end of said frame, rotatably-driven means carried by said base and eccentrically engaging the other end of said frame for transmission of circular motion in a horizontal plane thereto, a classifying table carried by said frame and positioned with its intake end adjacent said pivotal connection and its discharge end adjacent the other end of said frame, means for feeding comminuted material to the intake end of said table, a circular, shallowly-concaved, supplementary classifier hinged to and for agitation with the end of said frame beyond and in position to receive the material from the discharge end of said table, and means engaging between said frame and said supplementary classifier to support and adjustably position the latter for actuation through a vertical arc relative to the former, whereby material fed to said table is subjected to uniform agitation longitudinally of the table and supplementary classifier and to simultaneous lateral agitation in-

creasing in amplitude as the material approaches the discharge end of the apparatus.

2. Apparatus of the character described comprising, in operative combination, a fixed base, a frame carried by said base and movable horizontally thereof, pivotal means fixed to said base and slidably engaging one end of said frame and rotatably-driven means carried by said base and eccentrically engaging the other end of said frame for transmission of circular motion in a horizontal plane thereto, a classifying table carried by said frame for vertical adjustment thereon and arranged with its intake end adjacent said pivotal connection and its discharge end adjacent the other end of said frame, means for feeding comminuted material to the intake end of said table, a circular, shallowly-concaved, supplementary classifier, having a diameter substantially equaling the width of said classifying table, hinged at one side to and for agitation with the end of said frame beyond and in position to receive the material from the discharge end of said table, and means engaging between said frame and said supplementary classifier to support and adjustably position the latter for actuation through a vertical arc relative to the former, whereby material fed to said table is subjected to uniform agitation longitudinally of the apparatus and to simultaneous lateral agitation increasing in amplitude as the separatory affects progress and the material approaches the discharge end of the apparatus.

3. In apparatus of the character described having, a fixed base, a frame carried by said base and movable horizontally thereof, pivotal means fixed to said base and slidably engaging one end of said frame and rotatably-driven means carried by said base and eccentrically engaging the other end of said frame for transmission of circular motion in a horizontal plane thereto, a classifying table carried by said frame for vertical adjustment thereon and arranged with its intake end adjacent said pivotal connection and its discharge end adjacent the other end of said frame, a plurality of uniformly-sized, semispherical cups substantially filling the classifying surface of said table, whereby material passing along said table is subjected to more rapid and more violent agitation as it progresses toward the discharge end thereof, means for feeding comminuted material to the intake end of said table, a circular, shallowly-concaved, supplementary classifier, having a diameter substantially equaling the width of said table, hinged at one side to and for agitation with the end of said frame beyond and in position to receive material from the discharge end of said table, and means engaging between said frame and said supplementary classifier to support and adjustably position the latter for actuation through a vertical arc relative to the former, whereby tailings from said table may be subjected to agitation corresponding in orbit with and of greater amplitude and less violence than that imparted by said table.

WALTER PHILIP LAESCH.
